SAFETY APPARATUS

Walter E. Rose and Clarence W. Rose,
Denver, Colo.

Application February 13, 1941, Serial No. 378,710

17 Claims. (Cl. 227—36)

This invention relates to safety apparatus and especially to that class of safety apparatus which will carry a person from a position of danger to a position of safety.

The invention is peculiarly, but not exclusively, adapted for use in connection with oil derricks, the preferred embodiment now illustrated and described being designed to transport a workman, working upon such derrick, away from the derrick to a safe position distant therefrom whenever a dangerous condition occurs at the derrick, such, for example, as fire, which is frequently started as a result of the blowing of a well. Accordingly, the illustration in the accompanying drawings and the description in the following specification is in terms of application of the invention to oil derricks.

Objects of the invention are to provide an apparatus which will automatically be set in operation by a workman jumping or falling from his working position and will automatically carry such person to a position of safety, distant from such working position; to provide in such an apparatus for the attachment of the apparatus to the workman at all times while he is at work and in such a manner that the attachment of the apparatus will be of assistance rather than hindrance to him in the performance of his work; to provide, in such apparatus, suitable means for absorbing or lessening the shock which would otherwise result from stopping the rapid movement of the workman attached to such apparatus while in operation; to provide convenience in the attachment and assembling of such apparatus; to provide a simple, inexpensive and durable apparatus of the class described, of comparatively little weight, but ample strength, to insure safety.

With the foregoing and other objects in view, all of which will more fully appear in the following specification, the invention comprises certain novel constructions, combinations and arrangements of parts as will be hereinafter described and claimed, the preferred embodiment of which is illustrated in the accompanying drawings, in which:

Fig. 1 is a diagrammatic elevational view of an oil derrick with our safety appliance installed.

Fig. 2 is a diagrammatic view of the structure illustrated at Fig. 1, looking down from line 2—2 of Fig. 1.

Fig. 3 is a side elevation of the trolley assembly.

Fig. 4 is a section on line 4—4 of Fig. 3.

Fig. 5 is a fragment on line 5—5 of Fig. 4.

Fig. 6 is a detail view of the lock, partly in

section, and partly in elevation, taken approximately on line 6—6 of Fig. 3, but on an enlarged scale.

Fig. 7 is a detail view on line 7—7 of Fig. 6.

Fig. 8 is a rear elevation of the parts shown in Fig. 6, partly in section, on line 8—8 of Fig. 6.

Fig. 9 is a view the same as Fig. 6 but showing the parts of the lock in open position.

Fig. 10 is a plan of the stop assembly.

Fig. 11 is a section on line 11—11 of Fig. 10.

Fig. 12 is an elevation of the left end of the stop assembly as shown in Figs. 10 and 11.

Fig. 13 is a section on line 13—13 in Fig. 11.

Fig. 14 is a side elevation of the fragment of the stop assembly containing the cable-gripping jaws and associated parts.

Fig. 15 is a bottom view of the grip portion shown at Fig. 14.

Fig. 16 is a front elevation of the rope guide and trolley retaining and releasing assembly with parts broken away to show construction.

Figs. 17, 18 and 19 are fragmentary sections taken respectively on lines 17—17, 18—18 and 19—19 of Fig. 16.

The derrick is shown diagrammatically and is indicated generally by D and has the usual corner posts 20 and the usual angle iron girts 21, see Figs. 1, 2, 16, 18 and 19. The usual working platform, supported by the girts, and called the "board," is indicated at 22. Cable 23 is attached to derrick D in any suitable manner and at a suitable point above the board 22, as at 24, whence it inclines to a suitable anchorage 25 at such a distance from the base of the derrick as to give the desired inclination to cable 23, as illustrated at Fig. 1.

Four (4) main elements associated with the derrick and the cable and operating interrelatively, though not all simultaneously, constitute the apparatus which automatically assures safety, namely, the trolley assembly, generally indicated at T, Figs. 1 and 2, and shown in detail at Figs. 3 to 9, the safety-belt rope R, (Figs. 1, 3, 4, 5, 16 and 18); the combined rope-guide, trolley retainer and release indicated at G, at Figs. 1 and 2, and shown in detail at Figs. 16 to 19, and the releasable stop assembly indicated at S at Figs. 1 and 2 and shown in detail at Figs. 10 to 15.

The present invention lies in the combination of these elements and also in the structure and arrangement of the trolley assembly T, the rope guide G and the stop assembly S.

The trolley assembly, hereinafter referred to as the trolley, will be first described.

The trolley comprises a housing 26 in which sheave 27 is rotatably mounted by means of axle 28, the ends of hub 27a of the sheave 27 preferably extending laterally beyond the balance of sheave 27 and bearing against the inner walls of housing 26 to definitely center sheave 27, while confining within the area of the ends of hub 27a, the rotational friction between sheave 27 and the housing, all as clearly illustrated at Fig. 4.

The trolley assembly must be adapted to suspend the man who is to be carried to safety and, in order to be convenient, economical and efficient, should be adapted to admit the cable through the side of the housing so as to avoid the necessity of threading the cable through the trolley. Also, the securing of the trolley assembly in operative position upon the cable is necessary. These important functions are provided for by the structure shown at the lower part of Figs. 3 and 4, details being shown at Figs. 6 to 9.

It is preferable to suspend the man by and through a suitable shock absorber such, for example, as one of the type disclosed in our United States Letters Patent No. 2,175,571, and such a shock absorber is conventionally indicated at 29, provided with a lug 30, having an eye 31 adapted to receive hanger 32 (suspended from housing 26 as later described), for suspending the shock absorber.

The rope R, attached to the safety belt on the man, as later described, runs through the shock absorber 29 and is gripped and held thereby, except when subjected to excessive pull, as by the falling of the man attached thereto, under which conditions, it slips through the absorber sufficiently to ease the shock. All this is hereinafter more fully described.

As shown at the right at Fig. 4, the trolley assembly includes a carrier for a reserve supply of the rope R, which carrier will be later described.

The rope R runs from the carrier through hanger 32 and down over the top of lug 30 and through the shock absorber and, to afford a smooth surface for the rope, lug 30 is rounded at the top as at 30a, all as clearly shown at the bottom of Figs. 3 and 4.

Links 33 and 34 are carried by yoke 35 journaled in the lower portion of the long or closed side of housing 26. The journaling is conveniently accomplished by folding back against the housing an extension 26a of the closed side of the housing and enclosing yoke 35 in the fold, as at 36. The folded extension 26a preferably extends upwardly against the housing 26, furnishing reinforcement for the seating of axle 28, as at 28a, and is then bent outwardly to form a hanger 37 for the rope carrier which will be later described.

Links 33 and 34 are preferably V shaped, carrying, on their free tips, hooks 33a and 34a adapted for insertion through slots 38 of eyelets 39 and to engage the bottoms of the eyelets and be locked thereto as later described.

Eyelets 39 are carried by yoke 40 journaled in the lower part of the shorter or cable-receiving side of the housing 26 which journaling is conveniently accomplished by folding an extension 26b of housing 26 upon said shorter side of the housing and journaling yoke 40 in a part of the fold as at 41. Extension 26b extends upwardly against housing 26, furnishing reinforcement for the seating of axle 28 as at 28b.

Portions 26c of extension 26b are bent away from the body of the extension and cut away or notched as at 26d to receive the bent ends 42 of

forked springs 43, the bases or yokes of which are swingingly mounted in the ends of shafts 44 as indicated at 45.

Shafts 44 are rotatable in the enlarged circular portions 38a of slots 38 in eyelets 39 and on the inner side of eyelets 39 the shafts are provided with lugs 46 adapted to contact the bases of hooks 33a and 34a and lock the hooks in position when they are hooked through slots 38 as clearly shown at Figs. 4, 6 and 8.

The reserve rope carrier suspended from hanger 37 is illustrated at the right in Fig. 4 and a fragment thereof at Fig. 5. It is designed to carry a considerable length of rope in such a manner as to prevent tangles and still readily release the necessary length of rope when excessive pull causes rope R to slip through shock absorber 29. A convenient structure for thus carrying and, when required, paying out the rope, comprises a plurality of slats or fins 47, suspended from the hanger 37, in parallel, interrelatively spaced relation, the rope being looped at the top of each side of each fin and thus releasably held by a rubber band 48 or other suitable means adapted to suspend the weight of the rope itself by engagement with the loop thereof in the manner illustrated, but adapted to release the rope when strongly pulled, the release resulting from the stretching of band 48 or from compression of the loop or both. Fins 47 are illustrated as converging at their tops to a supporting pintle 49 carried by hanger 37, but any structure for supporting the fins from hanger 37 may be used.

In order to automatically assure safety to the man suspended from the trolley T rolling down cable 23, it is necessary to provide means for bringing the trolley to a stop before the man strikes the ground or the anchorage 25. This stopping point, however, must be far enough down cable 23 to be out of the area of danger created by the fire or other condition existing at the derrick. Keeping in mind that the man suspended from the trolley is traveling at a high rate of speed by the time he is clear of the danger area around the derrick, it will be obvious that a sudden stop would probably kill or at least injure the man. Accordingly, trolley-stopping means are provided on the cable 23, beyond the danger zone around the derrick, which means are adapted to ease the trolley, with its suspended man, gradually to a stop before the man contacts the ground or the anchorage 25. It is desirable that, from such stopping point, the man be eased down cable 23 to a point at which he can reach the ground.

The releasable stop assembly S, referred to generally as stop S, is provided to meet these requirements and is illustrated at Figs. 10 and 11 and in parts at Figs. 12 to 15. It has an inverted U shaped housing 50, the sides of which are recessed as at 51, the bottoms of the recesses 51 being further recessed as at 52 for purposes later described.

A top plate 53 is secured to the housing 50 by bolt 54 and extends considerably beyond housing 50 on both sides, as clearly shown at Figs. 10 and 12. A bottom plate 55, generally coterminous with plate 53 but notched at the corners as at 56, in order to seat in recesses 51, is attached to plate 53 by tie bolts 57.

Seated in the top of housing 50 and lying in cable 23 is upper jaw 58 of the cable grip, composed of bronze or other suitable material. Pins and bolts, later described and passing through

the upper jaw 58 as clearly seen at Fig. 11, hold the jaw in place in housing 50. The lower jaw 59, of the grip, V grooved as at 60, on its cable contacting side, and channelled, as at 61, on its under side, is vertically slidably positioned in the housing along the underside of cable 23 beneath jaw 58. Jaw 59 is likewise composed of bronze or other material suitable for a friction grip.

Trough 62 rests on plate 55 and is suitably attached thereto as by bolt 63. A row of coiled compression springs 64 is seated in trough 62 and capped by channel 61 and retained in position longitudinally of the trough and channel by bolts 65 connecting the trough 62 and jaw 59 through the two end coiled springs 64, as clearly shown at Figs. 11 and 12.

In order to release the grip of jaw 59 on cable 23, jaw 59 must be moved downwardly, and, in order to permit this downward movement, bolts 65 may slide down through trough 62 (when jaw 59 is depressed), or the heads 66 of bolts 65 may be slidably seated in jaw 59 so that the jaw 59 may slide downwardly with reference to said heads 66.

Arms 67 secured to the sides of the housing 50 by bolts 68 passing through the housing and upper jaw 58, extend generally in line with cable 23 and carry shaft 69 at their outer ends, sheave 70 being rotatably mounted on shaft 69 and adapted to roll on cable 23 and being enclosed by inverted U shaped housing 71, the lower tips of the sides of which housing converge, as at 72, to less than the diameter of cable 23 so as to normally retain the cable within the housing 71. The sides of housing 71 may, however, be sprung apart sufficiently to permit removal of the housing from the cable by passing the cable between tips 72.

Fulcrumed to housing 50, as by bolt 73, is a duplex lever having arms 74 extending beyond housing 71 and preferably converging as at 75 and carrying between their converged ends a pin or bolt 76 to which is attached the release rope 77.

Pin 78 extends through lower jaw 59 and projects therebeyond on both sides. The ends of pin 78 project through and beyond housing 50, and are vertically reciprocable in recesses 52. The ends of pin 78 which project beyond the housing 59 are engaged by notched fingers 79, pivoted to lever arms 74 as at 80, whereby, when lever arms 74 are pulled down by rope 77, fingers 79 will depress pin 78 and press jaw 59 downward, compressing springs 64 and lessening or releasing the grip on cable 23.

Fire and other dangerous situations at oil derricks occur so suddenly as to usually allow no time or opportunity for any intelligent action on the part of the man working on the derrick. Frequently the man is rendered unconscious or otherwise incapacitated from taking any action in his own behalf except jumping, rolling or falling from the board on which he is working.

Accordingly, one of the principal objects of this invention is to provide a wholly automatic safety system requiring no action on the part of the person in danger except his falling or jumping from the board on the derrick, until after he has been eased to a safe stop at a point beyond the danger zone.

Our safety apparatus, therefore, includes means by which the workman on the derrick is at all times attached to the safety apparatus in such a manner that it will not simply not in-

terfere with his carrying on his work on the board but, on the contrary, will actually secure and facilitate him in such movements and also in such manner and by such means that his jumping or falling from the board will automatically trip or release the apparatus and, likewise, automatically carry him to the predetermined point for a safe stop.

The rope guide, trolley retainer and release assembly illustrated at Fig. 16 and in sections and details at Figs. 17 to 19, meets these requirements and will now be described.

The assembly will be referred to as guide G. The operative mechanism of this assembly is suspended from a base plate 81, clamped to a girt 21 by tie bolts 82, positioned in front of and behind girt 21 with their lower ends engaging the plate 81 as at 82a and their upper ends engaging top plate 83 as at 82b, the rear of plate 83 resting on the upper edge of girt 21 as at 83a (Fig. 19) and the front of the plate 83 being supported by channeled spacers 84 resting on the forward edge of the girt, the front tie bolts 82 passing through the flanges 85 of the spacers. Such a structure may be clamped to any girt without tools or appliances other than a wrench to tighten the tie bolt nuts.

A shield 86, to protect, from the weather, most of the working parts, is preferably provided and may be attached to or formed integral with the base plate 81 and the flanges 87 and 88 next described.

Flanges 87 and 88 depend from plate 81 and have ears 87a and 88a. Bolts 89 and 90, with heads countersunk in plate 81 as at 89a and 90a project downwardly through ears 87a and 88a and carry, rotatable thereon, rollers 91 and 91a spaced apart a suitable distance for the operation of the rope R and the ring thereon as later described.

Frame 92 depends from plate 81 and top shaft 93 is seated in and extends through flanges 87 and 88 and the wall of frame 92 the shaft 93 being conveniently in form of a bolt with head 93a resting against flange 87 and nut 93b resting against the wall of frame 92. Top roller 94 is rotatably mounted on shaft 93 between flanges 87 and 88.

Sleeve 95 is rotatably mounted on shaft 93 between flange 88 and the wall of frame 92 and carries, affixed thereto, trip arm 96 and catch 97.

Frame 92 has a flange or ear 98 projecting therefrom and shaft 99 is mounted at one end in ear 98 and at the other end in flange 88. Bell-crank lever 100 is fulcrumed on shaft 99, being mounted thereon by spacer sleeve 101. The lower end of bell-crank 100 terminates in a hook or seat 102 for the bottom shaft later described. The upper arm of bell-crank 100 has at its terminus a notch 103 to receive catch 97 for normally holding the bell-crank 100 in position, as at Figs. 16 and 19, and a finger 104 adapted to contact shield 86 and limit the movement of the bell-crank when catch 97 is withdrawn from notch 103.

Bottom shaft 105 has eyelet 106, linked into U bolt 106a, depending from frame 92 and normally rests in seat 102 of the bell-crank and lies in notches 87b and 88b of flanges 87 and 88 and carries bottom roller 107, rotatable thereon, with collars 108 and 109 on shaft 105 to hold roller 107 in the proper position longitudinally of shaft 105.

U shaped trip bar 110 is swung on shaft 105

by eyelets 111 and 112 and bifurcated cam 113 is rotatably mounted on shaft 105 straddling eyelet 112. The two sides of cam 113 are provided with a series of paired holes 114 whereby trip pin 115 may be positioned in any one pair of holes.

In the position of the parts as illustrated at Fig. 17 the pin 115 supports one arm of trip bar 110 at an angle, the arms of trip bar 110 being illustrated at the same angle in Figs. 18 and 19, this being approximately the preferable angle for the trip or releasing operation hereinafter described. To make sure that the normal pressure of trip bar 110 on pin 115 will not move catch 97 out of notch 103, suitable means, such as leaf spring 116, are provided for holding catch 97 in notch 103 against any normal pressure of trip bar 110 upon pin 115 but spring 116 must not be strong enough to hold catch 97 against excessive pressure of bar 110 on pin 115 such as will be exerted when the man falls or jumps from the board, as later described.

Rope R is provided with suitable means to normally limit the movement of the rope through the rollers toward the trolley. Such means are illustrated at Figs. 16 and 18 as ring 117 of sponge rubber or other suitable material, which will grip the rope and will normally overlie rollers 91 and 91a and stop the movement of rope R to the right (referring to Fig. 18) when ring 117 contacts the rollers as illustrated at Fig. 18, except when excessive pressures or pulls are exerted in which case ring 117 will, by such excessive force, be compressed or distorted and pass with rope R, between the rollers as hereinafter described.

The operation of the apparatus will now be described, starting with the various parts in position as generally indicated at Fig. 1, wherein the rope R is shown as extending from the trolley T through the guide G to a point above the board 22. The end of the rope above the board 22 is to be attached to a safety belt of any suitable construction worn by the workman standing upon the board 22. The rope is adjusted so that its length from the trolley to the workman on board 22 is just sufficient to allow the workman to move on the board to the extent required by the usual operations, but short enough to prevent his going off of the board at any point except on the side beneath the guide G.

The rope extends from the trolley through the space between the four rollers, 91, 91a, 94 and 107. The ring 117 has a friction grip on the rope and overlies the rollers 91 and 91a and thus holds the trolley at the desired point on cable 23, as illustrated at Fig. 1, even when the workman on board 22 moves toward the guide G and thus slackens the part of the rope between the workman and the ring 117. Accordingly, so long as the workman is on board 22, the trolley is held in its upper position but the rope in no way interferes with the activities of the worker but on the contrary tends to make his position safer by preventing his going beyond the board in any direction except on the side beneath the guide G.

If the workman jumps or falls off the board 22 on the side beneath the guide G, the rope, being attached to him, will strike the trip bar 110 and move the same against the trip pin 115 and this action will rotate the cam 113 causing it to move the trip arm 96 which will lift the catch 97 out of the notch 103. The weight of shaft 105 with its roller 107 and the trip bar 110, all of which is supported in seat 102 of bell crank 100, will swing the bell crank downwardly as soon as catch 97 is removed from the seat 103. Before the bell crank

has moved downwardly sufficiently to cause finger 104 to contact the shield 86, shaft 105 will have slipped off seat 102 and the shaft with its roller 107 and the trip bar 110 and cam 113 will all swing downwardly below the U bolt 106a. Rope R will then be free to pass outwardly from the derrick between rollers 91 and 91a except for the resistance of ring 117 and this ring being of sponge rubber, or other suitable material or structure, will be compressed or distorted or released by the pull exerted on the rope resulting from the weight of the man suspended thereon so that the ring will pass between or become disengaged from the rollers and the man will then be suspended directly from the trolley which will immediately and automatically start downwardly on cable 23.

It will be understood that all of the above operation is practically instantaneous and that it all takes place automatically as a result of the man jumping or falling from the board 22. If by reason of the gradualness of the incline of cable 23, or for any other reason, the trolley does not move down the cable with sufficient rapidity to ease the shock resulting from the man falling to the end of the rope, the rope will, to the necessary extent in order to ease this shock, slide through shock absorber 29, using the reserve supply in the carrier so far as necessary for this purpose. Ordinarily, however, the freedom of the trolley to move downwardly on cable 23 will prevent any serious shock at this stage of the operation and the shock absorber 29 will not usually be called into play at this stage.

The trolley, with the man suspended therefrom, rolls down cable 23 until it contacts stop assembly S which is gripped to cable 23 between the jaws 58 and 59 and when the trolley strikes the stop S, two shock absorbing elements will be brought into play. The first is the grip of the stop on the cable 23, which is a resilient friction grip maintained by the springs 64 and which grip will obviously permit the stop to slide on the cable to some extent, depending on the force of the impact of the trolley and the forward momentum of the man suspended therefrom relative to the strength of the springs 64. Cooperating with this shock absorbing feature is the shock absorber 29. If the grip of the stop S on the cable is so strong that the stop will not slide on the cable sufficiently, the extra pull of the man on the rope R, resulting from the contact of the trolley with the stop S and the swinging forward of the man on rope R will cause the rope R to slide through shock absorber 29 and thus further ease the stopping of the man. In other words, the resilient grip of the jaws 58 and 59 on the cable and the shock absorber 29 cooperate and complement each other in absorbing the shock and bringing the man to a safe and easy stop. Either of these elements alone will ease the man to a stop more or less satisfactorily according to the exactness of its construction and adjustment but a satisfactory stop is better assured by the cooperative action of the two elements.

When the man has been brought to a stop as above described, he will be suspended on rope R from trolley T beneath stop assembly S. It will then be necessary for him to reach a place lower down on the cable 23 from which he can reach the ground or the anchorage at the end of the cable. In order to do this, he has only to reach out and grasp the rope 71, a downward pull on which will lessen the grip of jaw 59 on cable 23 and permit the assembly to slide down the cable to the desired final stopping place.

Should the man be unconscious, he will remain suspended until some other person pulls the rope 77 and permits the assembly to slide down the cable to the desired point, at which the man can be removed from the safety belt by which he is suspended on rope R.

In assembling the apparatus ready for the operation above described, it will be obvious that the stop assembly and the trolley can both be positioned on cable 23 without threading the cable there-through.

Referring to Fig. 12, it will be obvious that by removing tie bolts 57, the assembly comprising bottom plate 55, trough 62, springs 64, lower jaw 59 and pin 78 may be removed from the stop assembly as a unit. The balance of the assembly is then dropped over the cable 23 so that upper jaw 58 will rest on the cable which is between the sides of the housing 50 in the position illustrated in Fig. 12. Pin 76 will be removed from between the lever arms 74 so that the extremities of the lever arms 74 may be passed downwardly on either side of cable 23 to the position illustrated in Fig. 11. At the same time, the sides of housing 71 are sprung apart so that this housing may be moved down straddling the cable 23 and allowing sheave 70 to seat upon the cable. Pin 76 with rope 77 attached thereto is then replaced between the lever arms 74. The part of the assembly comprising lower plate 55, trough 62, springs 64, lower jaw 59 and pin 78 is then inserted in the position as illustrated in Figs. 11, 12 and 14 and the tie bolts are adjusted to tie the lower plate 55 to the upper plate 53 as illustrated most clearly in Fig. 12. The stop assembly is then ready for positioning on cable 23 and it may be slid on cable 23 to desired position by pulling on rope 77 thus releasing the grip.

The attachment of the guide assembly G to a girt 21 has already been described.

To attach the trolley T to the cable, the springs 43 are compressed so that their ends 42 may be withdrawn from the notches 26d and the springs 43 may be used as a handle to rotate shaft 44 and turn lugs 46 upwardly to the position illustrated at Fig. 9 so that hooks 33a and 34a may be withdrawn from eyelets 39 as illustrated at Fig. 9. The eyelets 39 may be swung upwardly on yoke 40 in journal 41, permitting the cable 23 to enter the housing beneath the journal 41, whereupon the trolley assembly is dropped so the sheave 27 will seat on the cable 23 as clearly illustrated at Figs. 3 and 4. Thereupon, eyelets 39 are dropped to normal position, hooks 33a and 34a are inserted through the eyelets. Shafts 44 are rotated by the springs 43 so as to cause lugs 46 to lock the hooks 33a and 34a in the eyelets in position illustrated in Figs. 3, 4, 6 and 8, and the hooks 43 are then compressed and the ends inserted through the notches 26d, whereupon, the ends 42 of the springs 43 will engage portions 26c of the housing and hold the assembly in the position as illustrated at Figs. 3, 4, 6 and 8 and ready for operation.

Rope R is then passed between rollers 91 and 91a and shaft 105 with its roller 107, trip bar 110 and cam 113 are swung into position as illustrated at Fig. 16 and the shaft 105 is seated in seat 102 as illustrated at Fig. 19. The ring 117 is adjusted on rope R so that it will lie against rollers 91 and 91a, holding the trolley at the desired point. The free end of rope R is then attached to the safety belt worn by the worker on board 22 and the apparatus is ready, in case

of blow out or fire or other danger, for the automatic operation first above described.

While we have illustrated and described many details of construction, equivalent alternatives will be obvious to those skilled in the art but such equivalent alternatives will be within the spirit and scope of the illustration, the specification and the appended claims, and we are not to be bound by the details of either illustration or specification.

We claim:

1. In an escape apparatus for structures, the combination comprising a cable inclined downwardly from the structure, a trolley on and adapted normally to move down the cable, a rope depending from the trolley and adapted for attachment to a person on the structure and to suspend such person from the trolley when not supported by the structure, rope-guiding means on the structure and means responsive to a downward pull on the rope to release the rope from the guiding means.

2. In an escape apparatus as defined in claim 1 the rope-guiding means including trolley retaining means adapted to normally engage the rope and thereby retain the trolley until the rope is released from the guide by a downward pull on the rope.

3. In an escape apparatus for structures, the combination comprising a cable inclined downwardly from the structure, a trolley on and adapted to move down the cable, a rope depending from the trolley and adapted for attachment to a person on the structure and to suspend such person from the trolley when unsupported by the structure, rope-guiding means on the structure releasable by downward pull on the rope and means attached to the cable distant from the structure and adapted, automatically upon contact of the trolley with said means, to decelerate the downward movement of the trolley and of the person suspended therefrom.

4. In combination with an escape apparatus as defined in claim 3, means associated with the decelerating and stopping means adapted to permit movement of the stopping means down the cable after the stop.

5. In combination with an escape apparatus as defined in claim 3, means associated with the decelerating and stopping means adapted, by manual operation thereof, to permit movement of the stopping means down the cable after the stop.

6. In combination with an escape apparatus as defined in claim 3, means carried by the decelerating and stopping means and adapted to be reached by a person suspended from the trolley and adapted to be operated by such person and, upon such operation, to permit movement of the stopping means down the cable.

7. In an escape apparatus as defined in claim 3, the decelerating means including a member frictionally gripping the cable and adapted, by said friction grip, to yield to the impact of the trolley with its suspended person and slide on the cable.

8. In an escape apparatus including an inclined cable and a person-carrying trolley thereon, trolley-decelerating means on the cable including a member frictionally gripping the cable and adapted, by said friction grip, to yield to the impact of the trolley with its suspended person and slide on the cable but to normally decelerate the movement of the trolley to a stop.

and means to lessen the grip of the member whereby to permit further movement of the trolley down the cable.

9. In an escape apparatus as defined in claim 8, the decelerating means including manually operable means to lessen the grip of the member whereby to permit further movement of the trolley down the cable.

10. In an escape apparatus as defined in claim 8, the decelerating means including manually operable means to lessen the grip of the member whereby to permit further movement of the trolley down the cable, said grip-lessening means being carried by the decelerating means within reach of a person suspended from the trolley.

11. In an escape apparatus for structures having a cable inclined downwardly from the structure, the combination comprising a trolley adapted to move on said cable, a rope carried by the trolley and adapted to normally suspend the dead weight of a person and means engaging the rope and adapted to deceleratingly pay out additional rope automatically responsive to a pull on the rope in excess of the dead weight of such person.

12. In a trolley assembly adapted to move on a cable and including a housing, means for opening the housing for admission of the cable thereinto and for thereafter closing and locking the housing comprising eyelets swingingly attached to one side of the housing and hooks linked to the other side of the housing and adapted to engage the eyelets, shafts rotatable in the eyelets and carrying lugs adapted, upon rotation of the shafts, to engage and lock the hooks when in interengagement with the eyelets and shaft locking means comprising forked springs journaled in the shafts and having ends adapted to engage a portion of the assembly which is fixed relative to the shaft.

13. In a safety apparatus for structures having a cable inclined downwardly therefrom and

a trolley on the cable, a decelerating assembly comprising, in combination jaws, adapted to yieldingly grip the cable and, upon impact of the trolley against the stop, to resistingly slide on the cable and automatically decelerate the movement of the trolley.

14. In combination with a decelerating assembly as defined in Claim 13, the jaws being carried in a housing and a sheave affixed to the housing and adapted to ride the cable and align the jaws therewith.

15. In combination with a decelerating assembly as defined in claim 13, manually operable means carried by the assembly within reach of a person suspended from the trolley and adapted to move the jaws apart.

16. In a stop assembly as defined in claim 13, upper and lower jaws carried in an inverted U-shaped housing having a bottom plate, a resilient structure between the lower jaw and bottom plate and the assembly comprising the lower jaw, bottom plate and resilient structure being adapted to be removed as a unit from the housing whereby to admit the cable within the housing.

17. In an escape apparatus for structures including a cable inclined downwardly from the structure and a trolley adapted to move along the cable and a rope carried by the trolley adapted for attachment to a person on the structure and rope-engaging means comprising a guide adapted to normally prevent substantial movement of the rope laterally but to permit free longitudinal movement of the rope therethrough, a stop on the rope adapted to engage the guide and limit the longitudinal movement of the rope toward the pulley and a trip assembly associated with the guide and adapted, by downward pull on the rope, to trip and open the lower side of the guide and release the rope therethrough.
